UNITED STATES PATENT OFFICE.

EDWARD P. ENDLICH, OF CUMBERLAND, WISCONSIN.

HOSE DRAINING AND DRYING REEL.

1,427,273.

Specification of Letters Patent. Patented Aug. 29, 1922.

Application filed April 25, 1921. Serial No. 464,334.

To all whom it may concern:

Be it known that I, EDWARD P. ENDLICH, a citizen of the United States, residing at Cumberland, in the county of Barron and 5 State of Wisconsin, have invented certain new and useful Improvements in Hose Draining and Drying Reels, of which the following is a specification.

This invention relates to hose reels, and 10 more particularly to devices whereby water may be drained from hose, such as fire hose. As is well known it is injurious to the fabric of hose, to permit water to remain therein for long periods of time. For 15 this reason, it is customary when returning from a fire to thoroughly drain the hose and dry same before the hose is again placed in readiness for future use. Many fire stations are equipped with long inclined platforms 20 upon which the hose is placed, while others suspend them from convenient places about the fire house. These practices require considerable space which is not always to be had at fire stations. Furthermore, during 25 the cold seasons of the year hose cannot be drained and dried outdoors.

It is an object of my invention to provide a reel upon which the hose may be drained and dried and which will require but little 30 floor space, can be handled by one man and will not injure the hose.

A further object of the invention is to provide a hose reel embodying certain features of construction whereby a relatively 35 small reel may be made to carry a large quantity of hose in draining and drying position, while at the same time the device is of simple and cheap construction, and capable of being knocked down for shipment.

40 A further object of the invention is to provide a device of the class described, which will have a heating unit within the coils of the hose so that the drying of the hose will be facilitated, this affording a 45 great advantage, in that the hose may be quickly and thoroughly dried.

To this end the invention consists in the construction, combination and arrangement of parts hereinafter described and claimed:—

50 In the drawings:

Figure 1 is a perspective view of my improved reel showing it removed from the base.

Figure 2 is a perspective view of the base.

55 Figure 3 is a semi-diagrammatic vertical sectional view showing the manner of

mounting the reel on the base and also the construction of the reel,

Figure 4 is a perspective view of an end 60 of one of the reel bars.

Figure 5 is a diagrammatic plan view of the heat unit, and

Figure 6 is a diagram indicating the two interspaced helixes defined by the winding 65 hose.

A designates the stand or base, B the reel, and C sections of fire hose wound thereupon. The reel comprises a vertical standard or spindle 1, projected through the horizontally disposed spiders 2 and 3, and secured 70 respectively on the standard by the set screws 4 and 5. The spider 2 is spaced a distance from the pivot end 6 of the standard, the latter rotatably fitting the bore 7 of the base A, and resting with its pivot end 75 in the bottom thereof. The spider 2 is slightly spaced from the top 8, of the base so that it may freely rotate above the latter.

At its top the standard 1 is turned to reduced diameter to form a shoulder 9, said 80 reduced part fitting the central bore of the spider 3. As shown this spider is considerably smaller in diameter than the spider 2, so that the reel bars 10 when secured to the spider by the bolts 11 will be inclined 85 upwards and inwardly to form a lattice work cone.

Any number of bars may be used, I having shown eight in the drawings, the bars extending a distance above the top 90 spider 3 and below the lower spider 2. Ex-

tending at right angles from the outer face of the bars are the supporting pins 12. These pins are arranged on the several bars in lines winding around the outer faces of the latter, describing a spiral helix. In the 95 drawings are shown, two such helixes, one wound within the other so as to form a double helix, similar to a double screw thread. This is illustrated in the diagram

(Fig. 6) wherein the two helixes are distinguished from one another by light and heavy lines. The supporting pins 12, are indicated only on the heavy line helix, to 100 avoid confusion, by heavy dots, to illustrate how they are arranged in series, on the bars to support a hose wound in a coil having a vertical axis.

By winding the hose in a double helix, I secure a greater pitch, which contributes to the efficiency of the invention in that the hose will drain faster, and 105 avoid the possibility of pockets being formed by sagging between the pins. The

pins may be made of any suitable length, so that a number of layers of hose may be supported on one series of pins. In Figure 3, is illustrated, how four layers of hose are supported in superposed relation, on one pin, the hose being shown slightly flattened after the manner of fire hose. To support the upper ends of the superposed layers of hose in a side by side position, in view of the usual coupling rings 13, I provide for each layer of hose a relatively long outstanding arm 14 forming a support for the latter, said arm having spreaders 15 extending upwardly in spaced relation, from the top thereof. The space 16 between the spreaders is less than the diameter of the coupling rings, so that in placing the hose on the reel, the spreaders serve as a stop for the coupling hose. As shown, the lower end of the hose will hang downward on one of the lower supporting pins. As the hose are wound, one upon another, the lower ends thereof will overlap so as to hang over separate pins owing to the increase in circumferential length with the addition of each layer of hose. The base A is preferably constructed with outstanding feet 17. Positioned preferably on the spider 2, is the heating unit 18, preferably in the form of a hollow ring surrounding the standard 1. In Figure 5, the unit is diagrammatically shown to consist of the usual electric heating coil 19, having terminals 20 leading to one of the reel bars 1, and being connected to an ordinary electric socket 21. An ordinary electric connecting plug 22 has electric connection with a source of current and is inserted in the socket when it is desired to use the heating unit.

40 It is to be understood, that other types of heating units may be employed.

In operation, the hose is placed on the reel as described, and the plug inserted in the socket 21. The heat from within the turns of the hose will pass around the coils of the latter to dry same. By making the reel conic in shape, the hose will cling to the reel bars more persistently than would be the case if the reel were of uniform diameter. This is demonstrated by the supporting pins which extend at right angles to the bars, as shown, inasmuch as the hose slides down the pins toward the bar, in the process of placing them on the reel.

I claim:—

55 1. The combination with a rotary hose reel, and a plurality of hose units, each having end couplings carried thereby, said reel being vertically disposed and having means for supporting the hose units in spiral formation, an arm extending laterally from the top, said reel and arm adapted to support the couplings of said units arranged in a row, and means engaging said couplings for holding the latter against displacement 60 from said arm.

2. A hose reel for supporting hose having end coupling members, comprising a base, a conic reel, rotatably mounted on said base having its large end downward, so as to rotate about a vertical axis, supports extending outwardly from the conic surface of the reel and positioned at intervals in a line encircling said reel and extending from the top of the latter to the bottom thereof, and 70 a relatively long outstanding support at the top of the reel formed with upwardly opening spaces narrower than the diameter of the hose coupling member.

3. A rotary hose reel for carrying a plurality of hose having end couplings, comprising a conic reel, an arm extending laterally at the top of the reel, means carried by said arm in engagement with the couplings of said hose for removably attaching 80 the hose to the arm, and hose supporting pins extending from the surface of the reel, said pins arranged to describe a plurality of interspaced spirals for the purpose set forth.

4. A rotary reel for carrying a plurality of hose lengths each hose having end couplings, comprising a conic upright reel, means at the top of the reel for removably attaching the couplings of the hose in successive positions to the reel, and hose supporting pins extending from the surface of the reel and arranged consecutively thereon to describe a plurality of interspaced spirals, the pins of each spiral adapted to receive a plurality of hose lengths wound in superposed relation from said attaching means around the reel.

In testimony whereof I affix my signature in presence of a witness.

EDWARD P. ENDLICH.

Witness:

GEORGE VOELKER.
